UNITED STATES PATENT OFFICE.

NILS T. CLEMENTS, OF SUPERIOR, WISCONSIN.

OUTLET-BOX CONSTRUCTION.

Application filed May 12, 1920. Serial No. 380,737.

To all whom it may concern:

Be it known that I, NILS T. CLEMENTS, a citizen of Sweden, residing at Superior, in the county of Douglas and State of Wisconsin, have invented certain new and useful improvements in Outlet-Box Construction, of which the following is a specification.

The invention has for an object to effect improvements in outlet boxes for electric installations. A particular purpose of the invention is to effect an improvement in such devices whereby armored cable may be quickly and securely fastened when entered in such a box, in a new and efficient way. In this direction it is also a purpose to enable the use of the same elements by which outlet openings in the box are closed to be used also as securing devices for cables entered through the openings. A related object is to enable the use of a single plate to close one or both of two openings, or to leave them both open, and at the same time serve to secure either one or two cables as required.

Another aim of the invention is to effect an improvement in the manner of forming and assembling a box of a plurality of sheet elements connected at abutting edges, and particularly whereby the provision on side walls on a box of a fastening for a plate disposed therebetween may be effected in a new and novel way. It is also an aim in this connection to give a means for supporting against one side element of a box an abutting edge portion of another side element, against movement transversely to its plane, in either direction.

Another specific object of the invention is to effect an improvement in outlet boxes constructed for gang assembly or for use singly.

A still further aim of the invention is to provide an improved form of lath rest in devices of this character.

The invention involves additional objects, advantages and features of invention as will be understood from the following description and accompanying drawings of one embodiment thereof.

Figure 1 of the drawings being an end view of a box constructed in accordance with my invention,

Fig. 1^a is a similar view showing the clamp gate in use.

Fig. 2 is a back view thereof,

Fig. 3 is a perspective view, of the same

Fig. 4 is a fragmentary front view of a box,

Fig. 5 is a fragmentary side view showing the lath rest,

Fig. 6 is a detail for the blank for the outer wall portion of the box,

Fig. 7 is a similar view of the blank for the back and inner wall portions,

Fig. 8 is a plan of the blank for the lath rest,

Fig. 9 is a detail elevation of the manner of fastening to one plate an abutting edge portion of another,

Fig. 10 is a fragmentary sectional view of the foregoing method of attachment,

Fig. 11 is a plan of the blank for the body of a box of modified form,

Fig. 12 is a similar view of the blank for the side of such a box,

Fig. 13 is a front view of such a box assembled, for a single gang,

Fig. 14 is a similar view of a two gang assembly of similar construction,

Fig. 15 is a detail of the box body for gang assembly,

Fig. 16 is an end view of a single gang box,

Fig. 17 is a fragmentary side elevation thereof.

There is illustrated in Figures 1 to 8 an outlet box especially suited for new work, adapted to be secured against the side of a stud, with means for supporting laths, where the lathing is interrupted to permit entering

of the box. The box includes a stud plate 10, forming at the same time one vertical side of the box as customarily put in place,

an integral bottom or back side 11 of the box being formed integrally therewith. The remaining sides of the box are formed in one piece 12, shown in Fig. 6, which is bent so as to form an outer side 13 opposed to the side 10 and ends 14 of duplicate form.

In the blanks for the plate 10 and piece 12, shown in Figures 7 and 6, the lines upon which the blanks are bent to shape the device are indicated by dotted lines. The plate 10 is longer than is necessary for the length of

the box, whereby a projecting flange 15 is formed at each end alined with the body of the plate, but on each end a slit is formed as at 16 in Fig. 7 in alinement with the end of

the box, forming an ear 17, which is bent to lie at right angles to the flange 15 so that it may project over the face of a stud against

the side of which the flange 15 is disposed,

enabling the securement of a box from the front by heavy screws, when necessary. The flanges 15 are also apertured at their rear part, so that the box may be secured adjacent the rear part to the side of the stud by screws. The usual switch mounting is provided for at 18. Upon the outer side of the side wall 13 of the box there is secured a lath rest, 19, which may be formed of wood as shown in Fig. 3, so that lath ends may be nailed thereto, or may consist of a metal lath fastening and rest device as shown at 20, in Figures 4 and 5, which is thought preferable. In this instance, the rest is formed of a single blank such as shown in Fig. 8, provided on one edge with a series of teeth 21 which are preferably so shaped that they may be forced into the end of a lath without objectionably splitting the same, to hold the lath against transverse movement. The opposite longitudinal edge 22 of the blank is planiform. The blank is then bent upon parallel longitudinal lines 23 which are spaced apart less than the thickness of a lath, and nearer the toothed edge of the blank than to the plain edge. The outer edge portions are bent so as to extend at right angles to the intermediate portion 24 which is apertured or otherwise adapted to be secured to the side wall 13 of the box. By reason of the bend being formed further from one edge than the other as mentioned, the part 20 serves as a supporting flange 25 as shown in Figures 4 and 5, located toward the bottom of the outlet box, so that when a lath is rested thereon and pressed against the toothed edge 21, it may be nailed at the opposite end or other parts to adjacent studs in the usual way, but the end engaged with the rest 20 will be held and properly supported to withstand pressure from the face of the wall without nailing or the use of any other fastening means, and will also be held in rigid relation to the box, so that after fastening and completion of the electrical installation, operation of the switch devices or the like installed in the box or pressure on the wall will not tend to crack the plaster by reason of relative movement between the box and fastener, which often occurs due to the yielding quality of the lathing or because it is insufficiently supported.

The end portions 14 are each formed with two openings 26, the edges of which next to what will be termed the bottom edge 27 of the blank are toothed, the openings being somewhat enlarged at the toothed edge so that the teeth will provide an opening of suitable size to readily receive the loom or other electrical conduit. A closing gate 28 is provided for these openings, consisting of a plate of a suitable size to cover both of the openings simultaneously, having a transverse slot 29 therein through which a bind-

ing screw 30 is engaged in a suitable threaded aperture 31 formed in the blank 12. One edge of the gate 28 is provided with a central extension 32 and end extensions 33 so that semi-circular recesses or bays 34 may be formed in the lateral edge of the plate adjacent the ends. Teeth are formed on the adjacent edge portions of the plate 28 throughout its length, for a purpose to be explained. Initially, the plate will be adjusted over both openings, so as to close them as shown at the far end of Fig. 3, and the screw 30 then tightened so as to hold the plate securely in closing position.

When the device is used in an insulation, should it become necessary to use one of the openings, the screw 30 is loosened, and the plate 28 rotated thereon so as to swing one end downwardly toward the bottom of the box and thence laterally and outwardly, to the position shown in Fig. 1^a, when one opening will be uncovered, and the part of the plate originally disposed thereover will be disposed over the opening. The loom or other conduit may then be introduced in the uncovered opening, the screw 30 having been slightly tightened, and by driving upon the straight back edge 35 of the plate, the toothed extension 32 will be driven into engagement with the loom or conduit so as to hold it securely against rotation or withdrawal from the opening; and maintaining suitable pressure upon the plate while further tightening the screw 30, the clamping of the conduit will be made permanent. In case it should be desired to use both openings at one end of the box, the plate 28 is further rotated upon the screw 30 to the position shown in Fig. 1, and when the loom or other conduit is introduced in the openings the plate may be driven into engagement with both conduits so that the teeth of the notches 34 will be pressed into engagement with the conduit coacting with the opposed teeth of the openings 26 to secure the loom against rotation or withdrawal, and the screw 30 similarly tightened to secure the two conduits. The one element thereby serves the function both of a closure for the outlet opening and as a clamp for conduits, taking the place of the ordinary knock-out plates and special bushings, nuts or other securing devices ordinarily employed. It is an advantage of my invention that the toothed edges of the openings 26 coacting with the toothed plate 28 prevent ordinary looms, or armored cable from unscrewing, by bodily rotation of the conduit, which sometimes occurs even when the conduit is securely held against longitudinal withdrawal directly.

In order to support the side 11 and hold it against displacement from its normal plane slits 36 are formed in the member 13 close to and parallel to the back edges thereof intermediate of the respective sides formed

therewith. The slits are spaced from the edges a distance corresponding to the thickness of the plate 10. The body of the box side above or forwardly of the slit is pressed 5 inwardly into a bowed shape so as to form a stop or lug 37. The metal at the outer side of the slit is forced outwardly in the plane of the side of which it is formed, and thence pressed inwardly over the back portion 11 10 and closely thereagainst, so as to form a retaining and supporting means which holds the back wall 11 against being pressed backwardly, as shown at 38 in Figures 1, 1^a, 2, 9 and 10. I customarily have heretofore effected 15 the latter operations as well as the formation of the back 37 after the bottom plate 11 has been put in place between the sides 13 and 14. The formation of the parts 38 and 37 has also been done in one operation 20 with a pointed tool angular in cross section which has been pressed against the metal at the upper side of the slit until the stop 37 is formed, and then by an outward pushing movement relatively to the box and 25 inward, extended over the abutting plate.

In Figures 11 to 17 inclusive there is illustrated a form of box which may be readily used for old or new work, and it is also especially advantageous in enabling the 30 ganging of boxes in such a manner that the assembled parts will be held very firmly in rigid relation, it being an objection to many present constructions of this kind that when ganged, it is not readily possible to secure 35 the parts in good aligned position with each other. This form of device is also well adapted for use in confined situations, requiring less room for conduits immediately adjacent the box than the usual form of outlet boxes. In this instance, the box includes 40 a body member 40, forming the back and top and bottom sides of the box, as well as integral mounting flanges 41 at top and bottom to engage over lath work and receive 45 mounting screws. For ordinary work, these body members 40 are constructed as shown in Fig. 11, being bent on a transverse line, to form an inset conduit inlet wall 42 extending at an oblique angle to the major back 50 portion, immediately adjacent which inset portion the metal is bent outwardly forming a shelf parallel to the plane of the body of the back as at 43 and thence extended a short distance to a line at which the outer 55 part of the blank is bent into a plane at right angles to the body of the back, the extreme end edge portion being bent outwardly at right angles to form the mounting flange 41. In the oblique portion 42 there 60 are formed two oval openings 46, the width of which is sufficient to loosely receive the ordinary loom of armored cable, the major dimension of the opening extending vertically and being slightly greater than the 65 width, extending nearly or quite the full

distance between the transverse limits of the oblique portion 42.

The box includes identical side members 48, which are formed with a contour at their inner side portions corresponding to the 70 form in which the body member 40 is bent, and of a size to lie against the edges of the body member 40, the edges of the sides being flush with the outer surface of the body 40. A rectilinear outer or front edge 49 75 is formed on the side members, and close to this at each corner there is formed an ear or tongue 50 at right angles to the plate beginning at a point inwardly of the edge 49 so that the tongue may extend under the 80 flange 41, the tongue having an upward extension at its outer part adapted to engage in rectangular apertures 51 formed in the flange 41 adjacent each side. The upper lateral edge portion of the body 48 is also 85 cut away at 45 to allow the flange 41 to project so that its outer or lateral edge lies flush with the outer face of the sides 48 as shown in Figs. 13 et seq. The side members are also formed with inwardly projected 90 tongues 52 positioned to engage over the shelf portion 43 of the body member, and tongues 53 are formed upon the back edge, bent inwardly so as to extend across the back and outer face of the back portion 41, 95 these being formed with threaded apertures to receive screws 54 engaged through suitable apertures in the back portion 41 at each side. If desired, a conduit inlet aperture 55 may be formed in the back portion 40 100 and closed by a pivoted shutter plate 56, one side of which is extended and recessed as at 57, the edge of which is toothed, so that it may act as a clamp for looms inserted through the aperture 55. The plate 56 is 105 secured by the same screw 54 which engages the ear 53 of the side 48, at one side of the box.

A combination closing and clamping plate 60 for closing or securing a conduit in the 110 openings 46 is provided, consisting of a single plate of a length and width sufficient to cover the opening when laid thereover and being extended a sufficient distance to provide a notched and toothed part 61 bent at the same angle to the remainder of the plate as that between the walls 41 and 42 of the box body. The plate 60 is provided with a central aperture in each side threaded 115 to receive a screw 62 inserted loosely through a suitable aperture in the back wall 41, at 63. The clamping part 61 is extended a sufficient distance from the plane part of the plate to project over the openings 46 a distance when the plane part of the plate is drawn snugly up against the bottom of the box. It will be readily appreciated that with the plate in one position the openings are closed and held securely closed by the plate when the screw 120 125 130

62 is tightened, and in the other position, by operating the screw to allow the toothed part to lie outwardly of the opening, a loom or other conduit may be inserted in each 5 opening, and then, by tightening the screw 62, the plate is drawn into forcible clamp and locking engagement with the conduit.

In order to permit ganging of such boxes, a body piece 40' may be provided, constructed in every particular, the same as the body member first described, with the addition of a locking ear 50' similar to the one 50 before mentioned, and extending from one edge of the body member only, the opening 51 being omitted at that side, and a back securing ear 53' similar to the one 53 formed upon the side elements 48, and offset so as to readily pass outwardly of the back of another body member, of the same form, the 20 ear being provided with a threaded aperture to receive the screw 54. If desired, the member 40' may have ears 65 formed at each side on the shelf portion 43, the ears at one side being offset downwardly from 25 the plane of the shelf, and at the other side being offset upwardly. These function in the same way as the ears 52 before mentioned.

What is claimed:

30 1. A box of the character described com-

prising a body plate forming two walls including one side, and a second plate member bent to form three walls abutting the first two to complete a box open at one side.

2. In a metal box construction a side element, a second element having an edge abutting the inner face of the first element close to its edge, the first element being formed with a slit adjacent the inner surface of the second element, the metal at the 35 inner side of the slit being inset over the abutting plate and the metal at the outer side of the slit being expanded and bent outwardly and inwardly over the outer face of the second named and abutting element. 40

3. In a metal box construction a side element, a second element having an edge abutting the inner face of the first element close to its edge, the first element being formed with a slit adjacent the inner surface of the second element, the metal at the outer side of the slit being expanded outwardly and bent inwardly over the outer face of the second named and abutting element. 45

In testimony whereof I have affixed my 50 signature in presence of two witnesses.
